UNITED STATES PATENT OFFICE.

THOMAS WILLIAM TODD, OF BEND, OREGON.

LOCK-PIN GRIP.

1,265,140.

Specification of Letters Patent.

Patented May 7, 1918.

Application filed May 29, 1917. Serial No. 171,710.

To all whom it may concern:

Be it known that I, THOMAS WILLIAM Todd, a subject of the King of Great Britain, residing at Bend, in the county of Deschutes 5 and State of Oregon, have invented certain new and useful Improvements in Lock-Pin Grips; and I do hereby declare the following to be a full, clear, and exact description of the invention, such as will enable others skilled in the art to which it appertains to 10 make and use the same.

This invention relates to new and useful improvements in lock pin grips, and the principal object of the invention is to provide a device for holding a watch against 15 loss or theft.

Another object of the invention is to provide a device which may be readily attached to or detached from an article of wearing 20 apparel.

Another object of the invention is to provide a device which may be used in connection with a pocket and which is so arranged that a watch may be hung within the pocket 25 and yet readily removed when so desired.

A still further object of the invention resides in the provision of a device having a pin by which it may be attached to an article of wearing apparel which pin may be locked 30 in closed position in order to avoid any possibility of the device being accidentally removed.

With these and other objects in view, the invention consists in the novel combination 35 and arrangement of parts which will be fully set forth in the following specification and accompanying drawings, in which:—

Figure 1 is a perspective view of a lock pin grip constructed in accordance with this invention;

Fig. 2 is a rear view in elevation of Fig. 1;

Fig. 3 is a fragmentary top plan view of Fig. 2 on an enlarged scale;

Fig. 4 is a vertical sectional view on line 45 4—4 of Fig. 1, looking in the direction of the arrows;

Fig. 5 is an edge view of a modified form of lock pin grip;

Fig. 6 is a rear view in elevation of Fig. 5;

Fig. 7 is a side elevation of a modified form of lock pin grip showing the same supporting a watch in the pocket of the user;

Fig. 8 is a side view of a further modified form of watch holder;

Fig. 9 is a view similar to Fig. 8 showing

the attachment in place for holding the watch rigidly in position;

Fig. 10 is a front elevation of Fig. 9 showing the watch removed;

Fig. 11 is a detail perspective view of the 60 attachment; and

Fig. 12 is a transverse sectional view on line 12—12 of Fig. 10.

Referring in detail to the drawings, 1 designates as an entirety the main body of the 65 device comprising a plate 2 having formed at the lower edges thereof, an attaching plate 3. This attaching plate 3 has formed integrally therewith the outwardly and upwardly extending ears 4 to which the jaw 70 member which will be more fully hereinafter described, is attached. A tongue 5 extends downwardly from the edge of the plate 3 on which the ears are formed and this tongue tapers toward its lower end as clearly shown 75 in the drawings. The lower terminal of the tongue 5 is bent back upon itself to form a spring tongue 6 to which is soldered at its upper end a pin 7 as clearly shown in Figs. 1 and 2. Formed near the lower end of the 80 tongue 5 is an off-set 8 which forms a shoulder beneath which the lower end of the clamping jaw which will be more fully herein-after described, engages. Formed at the upper end of the plate 2 is a thumb grip portion 85 which co-operates with the finger hold of the clamp jaw as will be more fully hereinafter described, thereby providing means by which the same is held.

A suitable hook 9 is attached to the outer 90 face of the plate 2 and forms a keeper for the end of the pointed pin 7 as clearly illustrated in Fig. 3. Secured to the inner face of the plate 2 and extending upwardly from a point near the lower edge thereof is a 95 spring 10 formed intermediate its ends with a push rod 11 by means of which the same is moved. The upper end of said spring is provided with a forwardly extending arm 12 carrying at its outer end a retaining plate 13 100 which co-operates with the keeper 9 in enclosing the pin 7 and holding it against accidental displacement.

The clamp jaw of the device is designated generically by the numeral 14 and comprises 105 the finger hold 15 having formed at its lower end the tongue 16, the lower end of which is curved inwardly to extend beneath the shoulder formed on the tongue 5 hereinbefore described. Formed at the point where 110

the finger hold and the tongue join and extending at right angles with relation to the inner face thereof are suitable hinged ears which are apertured to receive a pintle by means of which the clamp jaw is pivotally connected to the ears 4 of the attaching plate. Surrounding the pintle is a spiral spring one end of which bears against the tongue 5 while the opposite end of said spring bears 10 against the inner face of the finger hold 15 so as to normally tend to hold the tongue 16 in engagement with the tongue 5 beneath the off-set forming the shoulder 8.

In the modified form of watch holder 15 illustrated in Fig. 7, the main body of the device comprises the finger hold 21 formed at the upper edge of a vertical wall 22, the lower edge of which is provided with a horizontal extension 23 which terminates in a vertical shank 24 having formed integrally therewith a pin 25 which is bent back to form a loop and engages beneath a keeper 26 carried by the wall 22. A depending pin 27 projects downwardly from the edges of 20 the walls 22 and 23 and slidable on the pin 25 is a ball 28 which when slid upwardly in 25 the position illustrated in Fig. 7 receives the pin 27 and firmly holds the pins 25 and 27 against accidental opening. A jaw member 30 is pivoted to the end of the wall 23 on 30 which the shank 24 is formed and this jaw member is provided with a thumb piece 30 at its upper end which is positioned beneath the finger hold 21 while the lower end is 35 pointed as at 31 so as to project through an opening formed in the tongue 24 near its lower end.

In the use of the modified form it will be seen that the ring of the watch is passed over 40 the pin 25 and the pin is then locked as shown whereupon the watch and pins are placed in the pocket of the user with the clamped jaw 29 on the outside thereof in such position that the point 31 will pass 45 through the cloth of the pocket and enter the opening in the tongue 24 thereby securely locking the watch against movement.

In the modified form of the invention illustrated in Fig. 8, the main body comprises 50 a plate 32 formed at its upper end with a finger hold 33 and at its lower end with a bent back flange 34 which terminates in a horizontal flange 35. This horizontal flange or wall 35 is provided with a downwardly extending tongue 36 and at the point 55 where the tongue 36 joins the wall 35 are formed outwardly and upwardly extending ears 37 between which the clamped jaw is pivoted. Formed near the lower end of the tongue 36 is an off-set portion 38 to which 60 is removably secured by means of suitable screws 39, a pin 40, the point of which is retained beneath the flange 34 as clearly illustrated in Fig. 8. The clamped jaw is designated by the numeral 41 and is provided

with a bent back point 42 for engagement in the off-set portion 38 hereinbefore described. The said clamped jaw is pivoted as at 43 between the ears 37 and a spring 44 normally holds the clamped jaw in the position illustrated in Fig. 8. A thumb piece 45 is formed on the clamped jaw and co-operates with the finger hold in which the device is being put in place. In the use of the device above described, it will be understood that the watch loop is slipped over the pin as illustrated in Fig. 7, but upon reference to Fig. 9 it will be seen that a slight alteration of the device illustrated in Fig. 8 by the removal of the pin 40 will render the device capable of rigidly holding a watch as will be more fully hereinafter described.

In order to rigidly hold a watch in place, the screws 39 are removed and the pin 40 taken off whereupon a plate designated by 85 the numeral 46 is substituted in place of the pin and is provided with a slot 47 near its lower end to receive the screws 39 while the upper end is provided with a slot 48 to receive the gripping element of the watch 90 stem. A hook or loop 49 is formed at the lower end of the plate 46 and forms a rest or seat in which the lower edge of the watch engages. The upper slot 48 is adapted to receive the shank 50 of the clamped jaws 51 95 which shank is threaded into an aperture formed in the tongue 36 near its upper end. In use it will be seen that the watch is first placed in position by slipping the ring over the finger piece 33 and then downwardly 100 over the plate 32 and the flange 34 and onto the horizontal flange 35 as illustrated in Fig. 9. The lower end of the watch is then positioned within the loop 49 and the stem passed between the clamped jaws 51. It will 105 thus be seen that the watch will be rigidly held in position and the device may be placed in the pocket of the user in the manner illustrated in Fig. 7, or it may be attached to the pocket in such a position as to allow the 110 watch to be exposed.

While in the foregoing there has been shown and described the preferred embodiment of this invention, it is to be understood that such changes may be made in the combination and arrangement of parts as will fall within the spirit and scope of the appended claims.

What is claimed is:—

1. In a lock pin grip, a body, a clamped member pivoted to the body and adapted to engage over the pocket of a wearer, and watch supporting means removably attached to the body.
2. In a lock pin grip, a plate, a finger hold 11 at the upper end of the plate, an inwardly off-set extension at the lower end of the plate, a clamp member, a thumb piece on the clamp member positioned adjacent the finger hold, a clamping tongue on the clamp mem-

ber coöperating with the offset extension for engagement over the pocket of the user, and a watch supporting means removably attached to the extension.

5. 3. In a lock pin grip, a body, a clamped member pivoted to the body and adapted to engage over the pocket of a wearer, and a pin removably attached to the body.

10. 4. In a lock pin grip, a body, a clamped member pivoted to the body and adapted to engage over the pocket of a wearer, a pin removably attached to the body, and a latch to lock the pin in closed position with relation to the body.

15. 5. In a lock pin grip, a plate, a finger hold at the upper end of the plate, an inwardly extending extension formed on the lower end of the plate, a downwardly extending tongue formed on the outer end of 20 said extension, a clamp member secured to

said inwardly extending extension, a thumb piece on said clamp member positioned adjacent the finger hold, a clamping tongue on the clamp member adapted to coöperate with the tongue for engaging over the pocket of 25 the user, and a watch supporting means formed on the lower end of said tongue, as and for the purpose specified.

6. In a lock pin grip, a body, a clamped member pivoted to the body and adapted to 30 engage over the pocket of a wearer, a watch supporting means formed on the body, and a pin attached to the watch supporting means, as and for the purpose specified.

In testimony whereof I affix my signature in presence of two witnesses.

THOMAS WILLIAM TODD.
